UNITED STATES PATENT OFFICE

115,698

DESIGN FOR A LACE

Isaac Zendman, Jr., New York, N. Y.

Application May 25, 1939, Serial No. 85,192

Term of patent 3½ years

To all whom it may concern:

Be it known that I, Isaac Zendman, Jr., a citizen of the United States of America, residing in New York city, in the Borough of Manhattan, county and State of New York, have invented a new, original, and ornamental Design for a Lace, of which the following is a specification, reference being had to the accompanying drawing, forming a part thereof, wherein

The figure is a plan view of a piece of lace showing a complete unit of my design between the selvage edges of the lace.

I claim:

The ornamental design for a lace, substantially as shown and described.
